UNITED STATES PATENT OFFICE

139,664

DESIGN FOR A MOTORIZED PREFLIGHT TRAINER

Volmer S. Jensen, Glendale, Calif., assignor to
California Aero Glider Co., Inc., a corporation
of California

Application September 10, 1943, Serial No. 111,091

Term of patent 14 years

(Cl. D71—1)

To all whom it may concern:

Be it known that I, Volmer S. Jensen, a citizen
of the United States and a resident of Glendale,
in the county of Los Angeles, State of California,
have invented a new, original, and ornamental
Design for Motorized, Preflight Trainer, of which
the following is a specification, reference being
had to the accompanying drawing, forming part
thereof.

In the drawing:
Figure 1 is a side elevational view of a motorized
pre-flight trainer showing my new design;
Figure 2 is a front elevational view; and
Figure 3 is a top plan view thereof.

I claim:
The ornamental design for a motorized pre-
flight trainer, as shown.

VOLMER S. JENSEN.
